UNITED STATES PATENT OFFICE.

JOHN SIMONDS, OF BERKELEY, CALIFORNIA.

DESIGN FOR A MEMBER FOR SAW-HANDLES.

SPECIFICATION forming part of Design No. 32,795, dated June 5, 1900.

Application filed January 25, 1900. Serial No. 2,806. Term of patent 3½ years.

To all whom it may concern:

Be it known that I JOHN SIMONDS, a citizen of the United States, residing at Berkeley, county of Alameda, State of California, have 5 invented and produced a new and original Design for a Member for Saw-Handles, of which the following is a specification, reference being had to the accompanying sheet of drawings, forming a part thereof.

10 In the drawings, Figure 1 is a side view in elevation of the member. Fig. 2 is a top plan view of the same, and Fig. 3 is a perspective view of the member.

15 As shown in the accompanying sheet of drawings, the leading or material feature of my design consists of the supporting-post A, having an enlarged head *a* at one end and a concave face-plate *a'* at the opposite end.

To the upper surface of the enlarged head *a* of the supporting-post is attached the guard-plate B, which plate projects at a right angle to the said enlarged head *a*. This guard-plate is provided with a longitudinal groove or channel *b*.

Having thus described my invention, what 25 I claim as new, and desire to secure protection in by Letters Patent, is—

The design for a member of a saw-handle, as herein shown and described.

In testimony whereof I affix my signature, 30 in the presence of two witnesses, this 5th day of January, 1900.

JOHN SIMONDS.

In presence of—

N. A. ACKER,
D. B. RICHARDS.
